UNITED STATES PATENT OFFICE

GUSTAVE W. BERTHOLD, OF CHICAGO, ILLINOIS

CIRCUIT CONTROLLER

Application filed November 21, 1927. Serial No. 234,356.

My invention belongs to that general class of devices known as circuit controllers and relates particularly to a controlling device arranged to permit the control of various circuits and apparatus controlled thereby in predetermined manners whereby changes in the operation of the devices may be readily made without error and in a minimum of time. The apparatus is particularly designed to be used in theaters and like places where it may be desired to control many lighting circuits and apparatus circuits so as to produce various effects, it being desirable and in most cases necessary to make changes almost instantaneously, and the present apparatus is designed to enable one operator to do accurately and almost instantaneously what would ordinarily require a number of operators considerable time with likelihood of many errors. The invention has among its objects the production of apparatus of the kind described that is simple, efficient, reliable and rapid in operation and satisfactory for use wherever found applicable. It has among its other objects the production of apparatus of the kind described that is safe and reliable and apparatus that does not require a specially expert operator. With the present apparatus herein described, the same has as an object the production of a circuit controller so designed that a plurality of circuits or apparatus operated in conjunction with said circuits may be controlled in various predetermined ways, but which apparatus may in an emergency or for any other reason be controlled independently of the other circuits without in any way affecting their operation. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a front view of my improved ap-

paratus, only a portion of the same being shown and portions being arranged back of the panel;

Fig. 13 is a sectional view taken substantially on line 13—13 of Fig. 4;

Fig. 14 is a view taken substantially on line 14—14 of Fig. 13; and

Fig. 15 is a diagrammatic view illustrating the operation of the device in use.

In the drawings, I have shown my invention embodied in apparatus which is particularly adapted to be used in theaters, and the like, to control the lighting circuits thereof. Thus, it is the usual practice to provide a plurality of circuits so that various combinations thereof may be employed at any desired time to produce any desired lighting effect.

The apparatus preferably comprises a housing or cabinet which is designated generally by the reference character 20 and may be of any suitable construction. In this instance, the housing 20 is preferably formed from sheet metal and comprises side, top, back and front walls and a suitable base 21. The front wall, which is designated by the reference character 22, is preferably provided with a plurality of hinged doors 25, 26 and 27, a lock 28 being preferably provided

so that the door 27 may be locked in its closed position for a purpose hereinafter set forth.

Mounted in the cabinet 20 are two substantially duplicate mechanisms which are adapted to control a group of circuits, the circuits being also controlled by a switch 30 which is common to both mechanisms. As best shown in Fig. 4, each of said duplicate mechanisms preferably comprises a shaft which is journaled in brackets 31 and 32 mounted in the cabinet. In one mechanism, the shaft is designated by the reference character 34 and in the other by the reference character 34a. I will now describe the mechanism associated with the shaft 34, but it is to be understood that similar mechanism is associated with the shaft 34a, the mechanism associated with the shaft 34a being identified by the same reference numerals to which the letter "a" is added.

Mounted upon the shaft 34 are a plurality of metallic disks 35, or the equivalent, which are preferably provided with lugs 36 engageable with a key-way 37 cut in the shaft 34. This construction constrains the disks to rotate with the shaft 34 but permits displacement of the disks along the shaft when the disks are being assembled therewith. The disks 35 are preferably held in spaced relation by a plurality of sleeves 39 which are mounted upon the shaft and are interposed between the disks. It will be noted that one of the sleeves 39 is interposed between one of the disks 35 and the bracket 32 and that another of the sleeves 39 is interposed between another of the disks 35 and a metallic disk 40 which is also constrained to rotate with the shaft 34. Mounted upon the shaft 34 to the left (Fig. 4) of the disk 40 is a wheel or dial 42 having a plurality of suitable symbols 43 upon its periphery, which symbols 43 assist the operator or attendant in making certain adjustments in the mechanism as hereinafter explained. Interposed between the dial 42 and the disk 40 is a spacing sleeve 44 and a nut 45 screw-threaded upon the shaft 34 bears against the wheel 42. The shaft 34 and the aforescribed mechanism carried thereby is electrically insulated from the bracket 32 by an insulating sleeve 47 and insulating washers 48. Constrained to rotate with the shaft 34 is a sprocket wheel 49 which is insulated from the shaft by an insulating sleeve 50. It is readily understood that the nut 45 may be manipulated to clamp the disks 35 and 40 between the sleeves 39 and 44.

As best shown in Fig. 10, each of the disks 35 is provided with a plurality of radially extending slots 52 which accommodate screws 53 and 54 (see Fig. 11). Each pair of screws 53 and 54 are adapted to secure a contacting member 55 to the associated disk 35, the arrangement being such that the contacting member 55 is clamped between the heads of the screws and the disk. Screw-threaded upon the screws 53 and 54 are nuts 57 and 58,

respectively, and interposed between the nuts 57 and 58 and the associated disk 35 is an arcuate spring member 59 provided with apertures 60 and 61 to accommodate the screws 53 and 54, respectively. The nut 57 is preferably provided with a groove 63 adapted to receive and engage a projection or lug 64 struck up from the arcuate spring member 59. Obviously, the nuts 57 and 58 may be manipulated to adjust the tension of the arcuate spring member 59 so that the contacting member 55 will be held against accidental displacement relative to the associated disk 35. The lug 64 prevents accidental displacement of the nut 57 upon the screw 53. In the illustrated embodiment of the invention, each of the disks 35 is provided with twelve contacting members 55 and each of these members 55 may be brought into a position wherein it will engage one of a plurality of bifurcated members 66 when the shaft 34 is rotated or the contacting member 55 may be brought into a position wherein it will not engage the bifurcated contacting member 66 when the shaft 34 is rotated (see Fig. 10). The bifurcated contacting members 66 are preferably secured by screws 68, or the equivalent, to a bar 69 which is preferably formed from some suitable electrical insulation. Each of the screws 68 electrically connects its associated bifurcated contacting member 66 with a metallic bar 70 suitably secured to a plate 80 which is preferably formed from electrical insulation. Electrical conductors hereinafter described are connected to the bars 70. It will be noted that the aforesaid bracket 31 is wound around the plate 71 and that the bar 69 is secured to the bracket.

A sprocket wheel 49 is operatively connected by a sprocket chain 72 to a metallic sheave 73 rotatably journaled upon a shaft 74 which is mounted in a housing bracket 75 secured to the front wall 22 of the cabinet 20. Referring to Fig. 5, it will be noted that the ends of the sprocket chain 72 are adjustably secured by screws 77 and 78 to a bracket 79 which is secured by a screw 80 to the sheave 73, the arrangement being such that the sprocket wheel 49 and the shaft 34 may be angularly displaced around their coincident axes of rotation by loosening one of the screws 77 and 78 and tightening the other. The bracket housing 75 is provided with a slot 81 in which a lever 82 rides. As best shown in Fig. 2, the lever 82 comprises a metallic tube 83 which is preferably of substantially rectangular cross section and has its inner end secured to lugs 84 preferably formed integral with the sheave 73. Mounted upon the lugs 84 and secured thereby by screws 86, or the equivalent, are plugs 87 which are preferably formed from electrical insulation. Rigidly secured to the plugs 87 are metallic bracket members 88 which carry binding posts 90 and

91. The purpose of this construction will presently appear.

Slidably journaled in the tube 83 is a lock 93 provided with an integral lug 94 which projects through a slot 95 formed in the tube 83. Projecting from the lug 94 is a pin 96, or the equivalent, engageable with a plurality of apertures or holes 98 provided in the housing bracket 75. In the preferred embodiments of the invention, the number of holes 98 provided in the housing bracket 75 equals the number of contacting members 55 provided upon each of the aforementioned disks 35, the diameters of the sprocket wheel 49 and the sheave 73 being such that each of the holes 98 corresponds to one of the contacting members carried by each of the disks 35 so that any one of the contacting members 55 upon any one of the disks 35 may be brought into engagement with its associated bifurcated contacting member 66 by bringing the lever 82 into a position wherein the pin 96 engages the proper aperture or hole 98.

Screw-threaded into the plug 93 is one end 25 of a rod 99 which has its other end slidably journaled in a handle 100 carried by the outer end of the tube 83. At its outer end, the rod 99 is provided with a button 101, or the equivalent, and interposed between the button 101 and the bottom of a recess 102 formed in the handle 100 is a compression spring 103 which yieldingly prevents displacement of the plug 93 when the pin 96 is to be disengaged from one of the holes 98. Also screw-threaded into the plug 93 is one end of a relatively short rod 105 which has its other end screw-threaded into a block 106 preferably formed of electrical insulation and carried by the block 106 is a brush or contacting member 107 engageable with the aforementioned metallic bracket members 88. The brush or contacting member 107 is preferably somewhat resilient, the construction being such that when the compression spring 103 holds 45 the pin 96 in place in one of the apertures or holes 98, the brush 107 engages the metallic bracket members 88 and electrically connects the binding post 90 with the binding post 91. As best shown in Fig. 6, I preferably provide 50 stops 110 and 111 which limit angular displacement of the lever 82.

Mounted in the cabinet 20 and disposed beneath the plate 71 is a plate 115 which is preferably formed from electrical insulation 55 and mounted upon the plate 115 are a plurality of switch devices 116, there being a switch device 116 for each of the disks 35. The switch devices 116 are substantially identical in construction and therefore it is 60 only necessary to describe one of them.

Each switch device 116 preferably comprises a bifurcated bracket 118 rigidly secured to the plate 115 and journaled in each bracket 118 is a shaft 120 which carries a 65 disk 121 preferably formed of electrical in-

sulation. Each disk 121 is provided with a handle 122 whereby the operator may angularly displace the disk. Rigidly secured to each disk 121 are cooperating contacting members 127 and cooperating contacting members 128 which are rigidly secured in a metallic bar 129. Associated with each set of contacting members 128 is a relatively long contacting member 132 which projects from a metallic plate 133 secured by a screw 134, or the equivalent, to the plate 115. As best shown in Fig. 8, each contacting member 132 is of such length that it is engaged by the contacting members 128 when the handle member 122 is in the position wherein it is shown in full lines in Fig. 9 and when it is in the position wherein it is shown in dotted lines in the same figures. However, if the handle member 122 and its associated disk 121 are angularly displaced in a counterclockwise direction from the position wherein they are shown in full lines in Fig. 9, the contacting members 128 will be disengaged from the contacting member 132. When the handle member 122 and its associated disk 121 are 70 in the positions wherein they are shown in full lines in Fig. 9, the contacting members 127 engage a contacting member 135 which projects from a metallic bar 136 secured by a screw 138, or the equivalent, to the plate 115. When the handle member 122 and its disk 121 are in the positions wherein they are shown in dotted lines in Fig. 9, the contacting members 127 engage a contacting member 139 which projects from a metallic bar 140 secured by a screw 141, or the equivalent, to the plate 115. Each disk 121 is preferably provided with three notches 144, 145 and 146 engageable by a pin 147 carried by a plunger 148, the plunger 148 being slidably journaled in a tubular member 149 carried by the bracket 118. A compression spring 150 mounted in the tubular member 149 urges the pin 147 toward the disk 121. It is readily understood that when any one of the notches 144, 145 and 146 is engaged by the pin 147, the pin 147 prevents accidental angular displacement of the disk. In the present instance, the construction is such that when the notch 144 is engaged by the pin 147, the contacting members 128 engage the contacting member 132 and the contacting members 127 engage the contacting member 139, and when the notch 145 is engaged by the pin 147, the contacting members 128 are 100 still engaged by the contacting member 132 but the contacting members 127 are engaged with the contacting member 135. When the notch 146 is engaged by the pin 147, the contacting members 127 and 128 do not engage any of the contacting members 132, 135 and 139.

The aforementioned disk 40 is constantly engaged by cooperating contacting members 153 secured by rivets 154 or the equivalent, to 105

the bracket member 155 which is rigidly secured to the bar 69. Also secured to the bracket member 155 by the rivets 154 are spring members 156 which urge the contacting members 153 into engagement with the disk 40.

As best shown in Figs. 1 and 15, a signal lamp 158 is associated with each of the disks 35, each signal lamp being mounted in the front wall 22 directly above its associated disk 35. I also preferably provide a signal lamp 159 in connection with the switch 30 and a plurality of small lamps 160 and 160a associated with switches 151 and 161a, respectively. As best shown in Fig. 6, I preferably provide a switch 163 which is common to two sets of mechanisms associated with the shafts 34 and 34a, the switch 163 being mounted upon a bore 165 which is preferably formed of electrical insulation and is preferably mounted within the cabinet 20 in such manner that the switch is not accessible when the door 27 is closed.

Referring now to Fig. 15 wherein I have diagrammatically illustrated the members shown in Figs. 1 to 14, inclusive, the reference characters 170 and 171 designate electrical conductors which are connected to any suitable source (not shown) of electrical energy. For the purposes of this disclosure, the conductor 170 may be assumed to be the positive main and the conductor 171 may be assumed to be the negative main. It will be noted that I have shown the above described mechanism which is associated with the shaft 34 and also the mechanism which is associated with the shaft 34a. I have also assumed that the mechanism associated with the shaft 34 controls a plurality of lighting circuits which are installed in a theater, or the like, to light that part of the auditorium which is in front of the stage and that the mechanism which is associated with the shaft 34a controls a group of lighting circuits which provide light for the stage. As is well known to those skilled in the art, various lighting effects are obtained by using various combinations of these circuits. Thus, differently colored lamps may be employed in the various circuits or the lamps may be so disposed that they will give somewhat different results when used.

I preferably employ switches or relays 175 and 175a in connection with the mechanism associated with the shaft 34 and 34a. The switches 175 and 175a are preferably identical in construction and like parts thereof are designated by the same reference numerals. However, in case of switch 175a, I have added the letter "a" to the reference numerals. As diagrammatically illustrated in Fig. 15, the switch or relay 175 preferably comprises a solenoid 176 having a winding 177 and a movable core 178. Carried by the movable core 178 is an armature 179 having spaced contact-

ing members 180 and 181 which are electrically insulated from each other. The contacting members 180 and 181 are adapted to engage contacting members 183 and 184, respectively, when the winding 177 is energized. As shown, the contacting members 180 and 181 are connected to the conductors 170 and 171, respectively, and one terminal of the winding 177 is connected to the conductor 170. The other terminal of the winding 177 is connected to the binding post 91; the binding post 91 is, of course, adapted to be connected to the binding post 90 by the brush 107 and, in this instance, the binding post 90 is connected through the incandescent lamp 160 to one terminal of the switch 161 which has its other terminal connected to one terminal of the switch 163, the other terminal of the switch 163 being connected to one terminal of the switch 30. The remaining terminal of the switch 30 is connected through the incandescent lamp 159 to the conductor 171. The conductor which connects one terminal of the switch 161 to one terminal of the switch 163 is connected through the incandescent lamp 160a to one terminal of the switch 161a and the other terminal of the switch 161a is connected to the binding post 90a which may be connected through the brush 107a to the binding post 91a, the binding post 91a being connected to one terminal of the winding 177a which has its other terminal connected to the conductor 170. The contacting members 180a and 181a are connected to the conductors 170 and 171, respectively. The contacting members 183 and 183a are connected to the brushes 153 and 153a, respectively, and the contacting members 184 and 184a are connected to binding posts 187 and 187a, respectively, which are mounted in a junction box 188, or the equivalent. The binding post 187 is connected to a plurality of binding posts 190 and the binding post 187a is connected to a plurality of binding posts 190a. Each contacting member 66 is connected through a signal lamp 158 to a contacting member 135 and each contacting member 66a is connected through a signal lamp 158a to a contacting member 135a. Of course, a switch device 116 is provided for each of the contacting members 66 and identical switch devices 116a are provided for the contacting members 66a. However, I have shown only one of the switch devices 116 and only one of the switch devices 116a in Fig. 15, as this is sufficient for the purposes of this disclosure. The contacting member 139 of each switch 116 is connected to the conductor 170 and the contacting member 139a of each switch 116a is also connected to the conductor 170. Connected to the contacting member 132 of each switch 116 is a conductor 192 and connected to the contacting member 132 of each switch 116a is a conductor 192a. It is readily understood that there are twelve con-

ductors 192 and twelve conductors 192a. Connected to the binding posts 190 and 190a are conductors 193 and 193a, respectively, there being twelve binding posts 190 and twelve binding posts 190a so that twelve conductors 193 and twelve conductors 193a are provided. Each conductor 192 is paired with one of the conductors 193 and each of the conductors 192a is paired with one of the conductors 193a. Bridged across each pair of conductors 192 and 193 and across each conductor 192a and 193a are incandescent lamps 195 and 195a, respectively.

The operation of the above described apparatus is substantially as follows: I will assume that the switches 30, 163, 161 and 161a are in their closed positions and that the conductors 170 and 171 are connected to a suitable source (not shown) of electrical energy.

I will also assume that the levers 82 and 82a are in positions wherein their associated pins 96 and 96a engage the uppermost apertures or holes 98 and 98a, respectively. Of course, the contacting members 55 and 55a are arranged in rows and the construction is such that when the pins 96 and 96a engage one of the apertures 98 and 98a, respectively, one row of contacting members 55 and one row of contacting members 55a will engage the contacting members 66 and 66a, respectively, unless these contacting members 55a and 55 have been displaced radially of the disks 35 and 35a into positions wherein they will not engage the contacting members 66 and 66a. However, I am assuming that the members 55 and 55a are in positions wherein they will engage the contacting members 66 and 66a, respectively, when they are moved into registry therewith.

With the circuits and mechanism adjusted as indicated in the preceding paragraph, current will flow from the conductor 170 through the winding 177, the binding post 91, the brush 107, the binding post 90, the signal lamp 160, the switches 161, 163 and 30, and through the signal lamp 159 to the conductor 171 and current will also flow from the conductor 170 through the winding 177a, the binding post 91a, the brush 107a, the binding post 90a, the switch 161a, the signal lamp 160a, the switches 163 and 30 and thence through the signal lamp 159 to the conductor 171. Obviously, the solenoids 176 and 176a will be energized and the contacting members 180 and 181 will engage the contacting members 183 and 184, respectively, and the contacting members 180a and 181a will engage the contacting members 183a and 184a, respectively. An electrical current will then flow from the conductor 170 through the contacting members 180, 183 and 153, the disk 40, the shaft 34, the disks 35, a row of contacting members 55, the contacting members 66, the signal lamps 158, the contacting members 185, the contacting members 127, the

contacting members 128, the contacting members 132, the conductors 192, the lamps 195, the conductors 193, the binding posts 190, the binding post 187 and thence through the contacting members 184 and 181 to the conductor 171. An electrical current will also flow from the conductor 170 through the contacting members 180a and 183a, the disk 40a, shaft 34a, the disks 35a, a row of contacting members 55a, the contacting members 66a, the signal lamps 158a, the contacting members 135a, the contacting members 127a, the contacting members 128a, the contacting members 132a, the conductors 192a, the lamps 195a, the conductors 193a, the binding posts 190a, the binding post 187a and thence through the contacting members 184a and 181 to the conductor 171. Obviously, all of the signal lamps bridged between the conductors 192 and 193 and between the conductors 192a and 193a will be lighted. Now, if it is desired to extinguish any set of lamps 195, it is only necessary to angularly displace the disk 121, associated with that set of lamps, in such manner that the associated contacting members 128 are disengaged from the associated contacting member 132. Obviously, the same result may be obtained with respect to any set of lamps 195a by angularly displacing the associated disk 121a by means of its handle 122a.

Now, if it is assumed that the contacting member 55 which is shown in engagement with the contacting member 66 in Fig. 15, is displaced radially upon its associated disk 35 until it is disengaged from the contacting member 66, it is readily understood that the lamps 195 associated with that particular contacting member 66 may be lighted by bringing the contacting members 127 of the associated switch device 116 into engagement with the associated contacting member 139 whereupon current will flow through the switch 160 shown in Fig. 15. This current will flow as follows: From the conductor 170 to the contacting member 139 of the switch device 116, the contacting members 127 and 128 thereof, the contacting member 132 thereof, the associated conductor 192, the associated lamps 195, the associated conductor 193, its binding post 190, the binding post 187 and thence through the contacting members 184 and 181 to the conductor 171.

Of course, any one of the switches 160a may also be manipulated to light any set of lamps 195a when the associated contacting member 66a is not engaged by one of the contacting members 55a.

Now, if it is assumed that all of the contacting members 127 and 127a engage their respective contacting members 135 and 135a and all of the lamps 195 and 195a are lighted, it will be readily understood that any one of the switch devices 116 and 116a may be manipulated to extinguish the lamps 195 and 195a.

195a in any individual circuit. Thus, if the disk 121 of the switch device 116 shown in Fig. 9 is displaced in a counterclockwise direction (Fig. 9) until its contacting members 128 are disengaged from its contacting member 132, the lamps 195 associated with that switch will be extinguished.

As hereinbefore set forth, the wheels of dials 42 and 42a are provided with symbols 43 and 43a, respectively. The symbols are aligned with the rows of contacting members 55 and 55a and in the illustrated embodiment of the invention, the numeral 1 which will engage the contacting members 66 and 66a, respectively, when the levers 82 and 82a are in the positions wherein their pins 96 and 96a respectively, engage the uppermost holes or apertures 98 and 98a, respectively. The next rows of contacting members 55 and 55a are identified by the numeral 2 placed upon the dials or wheels 42 and it is readily understood that I prefer to number the several rows of contacting members 55 and 55a consecutively so that the numerals upon the dials 42 and 42a run from 1 to 12. The contacting members 55 or 55a of any row thereof may be arranged in any desired manner upon their disks 35 and 35a, thus some of the contacting members 55 of each row thereof may be brought into positions whereby they are engageable with contacting members 66 and the remaining contacting members of that row may be displaced toward the axis of rotation of the shaft 34 so that they will not engage the contacting members 66 when they are aligned therewith. Obviously, a relatively large number of combinations may be set up in the mechanisms carried by the shafts 34 and 34a and a relatively large number of lighting effects may be obtained by manipulating the levers 82 and 82a. If the levers 82 and 82a are moved into positions wherein a desired lighting effect is produced in a theater, or the like, and it is desired to "cut out" any lighted string of lamps 195 or 195a, it is only necessary to disengage the contacting members 128 or 128a from the contacting members 132 or 132a, respectively, of the proper switch device 116 or 116a. Also if it is desired to "cut in" any desired string of lamps 195 or 195a, it is only necessary to bring the contacting members 127 and 127a into engagement with the contacting members 139 or 139a, respectively, of the proper switch 116 or 116a.

If the lever 82a is in a position wherein a certain lighting effect is obtained upon a stage and it is desired to immediately darken the stage without altering the lighting condition in the remainder of the theater, it is only necessary to open the switch 161a and if it is desired to darken the theater with the exception of the stage without changing the position of the lever 82, it is only necessary to open the switch 161. If all of the

lights in the theater are to be darkened, this can be accomplished by opening either or both of the switches 30 and 163. It will be noted that the switch 132 is not accessible when the door 27 is in its closed position. Therefore, if the operator wishes to prevent any unauthorized person from attempting to adjust the apparatus to obtain new lighting effects, it is only necessary to open the switch 163 and lock the door 27 in its closed position. Obviously, the lighting system is then functionally inoperative.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In apparatus of the class described, a shaft, a disk mounted on said shaft and constrained to rotate therewith, a plurality of contacting members movably mounted in said disk and arranged circumferentially thereof, a plurality of yielding means frictionally engaging said disk for preventing accidental displacement of said contacting members relative to said disk, and a contacting member successively engageable by said plurality of contacting members when said shaft is rotated.

2. In apparatus of the class described, a shaft, a disk mounted on said shaft and constrained to rotate therewith, a plurality of contacting members slidably mounted on said disk, a plurality of yielding members secured to said contacting members and frictionally engaging said disk to prevent accidental displacement of said contacting members relative to said disk, means for adjusting the tension of said yielding means, and a contacting member successively engageable by said plurality of contacting members when said shaft is rotated.

3. Apparatus for controlling an electrical circuit comprising a supporting frame, a shaft journaled in said frame, a plurality of disks mounted on said shaft and constrained to rotate therewith, a plurality of contacting members carried by each of said disks, a plurality of contacting members mounted on said frame and engageable by the contacting members carried by said disks, means comprising a lever for rotating said shaft, a switch including a movable contacting member carried by said lever, and means carried by said lever for actuating said switch.

4. Apparatus of the class described comprising a shaft, a plurality of disks mounted on said shaft and constrained to rotate therewith, a plurality of contacting members

- adjustably mounted on each of said disks, a contacting member aligned with and spaced from each of said disks and engageable by said plurality of contacts carried thereby, being movable radially relative to said disks, a lever mounted to pivot about an axis spaced from the longitudinal axis of said shaft, and means whereby angular motion of said lever is transmitted to said shaft.
- 10 5. Apparatus of the class described comprising a shaft, a plurality of disks mounted on said shaft and constrained to rotate therewith, a plurality of contacting members adjustably mounted on each of said disks, a contacting member aligned with and spaced from each of said disks and engageable by said plurality of contacts carried thereby, a lever mounted to pivot about an axis spaced from the longitudinal axis of said shaft, and 15 adjustable means whereby angular motion of said lever is transmitted to said shaft.
- 15 6. In apparatus of the class described, a shaft, a disc mounted on said shaft and constrained to rotate therewith, a plurality of 20 contacting members mounted on and radially movable relative to said disc and arranged circumferentially thereof, a plurality of means engaging said disc for fastening said contacting means in adjusted position and 25 preventing accidental displacement of said contacting members relative to said disc, and a contacting member successively engageable by said plurality of contacting members when 30 said shaft is rotated.
- 30 7. In apparatus of the class described, a shaft, a disk mounted on the shaft and constrained to rotate therewith, a plurality of contacting members mounted on and arranged circumferentially of the disk, a contacting member mounted independently of 35 said disk and in spaced relation to the periphery thereof, individual mountings for each of said plurality of contacting members permitting the shifting of said members radially outwardly to a position wherein said members contact with said spaced apart contacting member, and a plurality of means engaging said disk for preventing accidental 40 displacements of said contacting means relative to the disk, said means permitting each of said plurality of contacting members to be separately shifted radially.
- 45 In testimony whereof, I have hereunto signed my name.
- 50 GUSTAVE W. BERTHOLD.
